CLAIM

The ornamental design for an array including adjustable lighting fixtures on a pole, as shown and described.

DESCRIPTION

FIG. 1 is a perspective view of one embodiment of the claimed design in a one-crossarm configuration with no center lighting fixture;

FIG. 2 is a front elevation view of FIG. 1 including a portion of the pole;

FIG. 3 is a back elevation of FIG. 1 including a portion of the pole;

FIG. 4 is a right side elevation of FIG. 1 including a portion of the pole;

FIG. 5 is a left side elevation of FIG. 1 including a portion of the pole;

FIG. 6 is a top plan view of FIG. 1;

FIG. 7 is a bottom plan view of FIG. 1 rotated 180degrees;

FIG. 8 is a perspective view of another embodiment of the claimed design in a two-crossarm configuration with no center lighting fixtures;

FIG. 9 is a front elevation view of FIG. 8 including a portion of the pole;

FIG. 10 is a back elevation of FIG. 8 including a portion of the pole;

FIG. 11 is a right side elevation of FIG. 8 including a portion of the pole;

FIG. 12 is a left side elevation of FIG. 8 including a portion of the pole;

FIG. 13 is a top plan view of FIG. 8;

FIG. 14 is a bottom plan view of FIG. 8 rotated 180degrees;

FIG. 15 is a perspective view of another embodiment of the claimed design in a three-crossarm configuration with no center lighting fixtures;

FIG. 16 is a front elevation view of FIG. 15 including a portion of the pole;

FIG. 17 is a back elevation of FIG. 15 including a portion of the pole;

FIG. 18 is a right side elevation of FIG. 15 including a portion of the pole;

FIG. 19 is a left side elevation of FIG. 15 including a portion of the pole;

FIG. 20 is a top plan view of FIG. 15;

FIG. 21 is a bottom plan view of FIG. 15 rotated 180degrees;

FIG. 22 is a perspective view of the claimed design in a six lighting fixture configuration;

FIG. 23 is an enlarged perspective view of the upper portion of the design;

FIG. 24 is a front elevation view of FIG. 23 including a portion of the pole;

FIG. 25 is a back elevation of FIG. 23 including a portion of the pole;

FIG. 26 is a top plan view of FIG. 23;

FIG. 27 is a bottom plan view of FIG. 23 rotated 180degrees;

FIG. 28 is a right side elevation of FIG. 23 including a portion of the pole;

FIG. 29 is a left side elevation of FIG. 23 including a portion of the pole;

FIG. 30 is a perspective view of the claimed design in an eighteen lighting fixture configuration;

FIG. 31 is an enlarged perspective view of the upper portion of the design;

FIG. 32 is a front elevation view of FIG. 31 including a portion of the pole;

FIG. 33 is a back elevation of FIG. 31 including a portion of the pole;

FIG. 34 is a top plan view of FIG. 31;

FIG. 35 is a bottom plan view of FIG. 31 rotated 180degrees;

FIG. 36 is a right side elevation of FIG. 31 including a portion of the pole;

FIG. 37 is a left side elevation of FIG. 31 including a portion of the pole;

FIG. 38 is an isolated back perspective view of the lighting fixture of FIGS. 1-37; and,

FIG. 39 is an isolated front perspective view of the lighting fixture of FIGS. 1-37.

The separations indicated by double break lines in FIGS. 2-5, 9-12, and 16-19 indicate the precise length of pole of the array including adjustable lighting fixtures on a pole forms no part of the claimed design. The broken lines at either end of each crossarm and at each lighting fixture entirely in broken line of FIGS. 1-21 indicate (i) the precise length of crossarms and (ii) the precise number of lighting fixtures (both total number and number per crossarm) of the array including adjustable lighting fixtures on a pole form no part of the claimed design; all other broken lines shown in FIGS. 1-21 indicate unclaimed portions of the array including adjustable lighting fixtures on a pole and form no part of the claimed design.

The separations indicated by brackets in FIGS. 22 and 30 and indicated by double break lines in FIGS. 24, 25, 28, 29, 32, 33, 36, and 37 indicate the precise length of pole of the array including adjustable lighting fixtures on a pole forms no part of the claimed design. The broken lines shown in FIGS. 22-39 indicate unclaimed portions of the array including adjustable lighting fixtures on a pole and form no part of the claimed design.
